ELECTRIC CABLE

William F. Lamela, East Paterson, N. J., assignor
to The Okonite Company, Passaic, N. J., a cor-
poration of New Jersey

Application July 28, 1938, Serial No. 221,692

5 Claims. (Cl. 174—116)

This invention is directed to electric cables, both single and multi-conductor, and has for one of its objects the provision of a cable which is highly fire-resistant and at the same time 5 moisture-resistant, well adapted for use inside buildings, power houses, on ships, etc.

In the accompanying drawing:

Fig. 1 shows a single conductor cable constructed in accordance with my invention; and 10 Fig. 2 is a cross section through a multi-conductor cable embodying my invention.

Referring to the drawing in detail and first of all to Fig. 1: 2 designates the cable conductor. Immediately about the conductor I apply asbestos rovings 4. This layer is saturated with flameproof compound. This compound may be made, for example, by mixing zinc oxide and calcium carbonate with benzine as the dispersing medium. This compound is water insoluble, non-conductive and will not decompose under heat or fire to leave a conducting path of carbon, and will not decompose or react in any way to form a conducting medium.

About the asbestos 4 I apply glass wool 6, preferably in the form of a serving of glass rovings. This serving is saturated with a flameproof compound similar to the compound with which the asbestos 4 is saturated.

Over the glass layer 6 I provide another layer 30 of asbestos 8 saturated with flameproof material.

About the asbestos layer 8 I apply a tape 10 consisting of a polymerized vinyl halide plasticized by a substantially non-volatile solvent and 35 frictioned into cotton sheeting. About this tape 10 I apply a wall 12 of a polymerized vinyl halide. The surface of this wall is painted with aluminum paint 14. An aluminum braid 16 is applied over the paint 14. The surface of this 40 braid is painted with aluminum paint.

The wall 12 is moistureproof but in the event of injury to this wall the cable will still be protected by the flameproof compound with which the asbestos layers 4 and 8 and the glass 6 45 are saturated, this compound not only rendering these materials flameproof but moistureproof as well. In addition this compound acts as a binder.

The construction illustrated in Fig. 2 is a multi-conductor cable. The conductors of this embodiment of my invention are designated 18. Asbestos rovings 20 saturated with a flameproof compound are applied about each conductor. The compound employed is the same as referred 50 to in connection with Fig. 1.

About the asbestos layer 20 of each conductor I apply glass wool 22, preferably servings of glass rovings also saturated with flameproof compound. About the glass layer 22 I apply asbestos rovings 24 also saturated with flameproof compound. 5

These conductors are then cabled over a center of asbestos 26 treated with the flameproof compound. Dry asbestos fillers 28 treated with flameproof compound are then added to provide 10 an assembly which is round in cross section.

About this assembly I provide a wall or layer 30 of asbestos, saturated with the flameproof compound and about this asbestos I apply a tape 32 similar to the tape 10 of Fig. 1, and over this 15 tape a polymerized vinyl halide wall 34 is applied which is painted with aluminum paint. An aluminum braid 36 is applied about the exterior of the cable and painted with aluminum paint. 20

It will be seen from all of the foregoing that I have provided a cable construction which is highly fire-resistant and at the same time moisture-resistant, the flameproof compound, as above pointed out, being of such a nature that 25 it will not decompose under the influence of heat or fire to leave a conducting path of carbon, and will not decompose or react to form a conducting medium.

It is to be understood that changes may be 30 made in the details of construction and arrangement of parts herein described and illustrated within the purview of my invention.

What I claim is:

1. An electric cable comprising in combination an electric conductor, asbestos layers and an intermediate layer of glass wool surrounding said conductor, said layers being saturated with a water insoluble, non-conductive flameproof compound incapable of being decomposed to a 40 conductive medium, a tape comprising a polymerized vinyl halide about the outer layer of asbestos, a polymerized vinyl halide layer about said tape, and an outer sheath about said last 45 mentioned layer. 35

2. An electric cable comprising in combination an electric conductor, layers of asbestos rovings and an intermediate layer of glass wool surrounding said conductor, said layers being saturated with a water insoluble, non-conductive flameproof compound incapable of being recomposed to a conductive medium, a tape comprising fabric filled with a plasticized polymerized vinyl halide about the outer asbestos layer, a 50 55

polymerized vinyl halide layer about said tape, and an outer metallic sheath.

3. An electric cable comprising in combination an electric conductor, asbestos layers and an intermediate glass wool layer, said layers being saturated with a water insoluble flameproof compound incapable of decomposing under heat or fire to form a conducting path of carbon, said layers surrounding said conductor, a polymerized vinyl halide layer surrounding said saturated layers, and an outer sheath about the vinyl halide layer.
4. An electric cable comprising in combination a plurality of electric conductors, each surrounded with asbestos layers and an intermediate glass wool layer, said layers being saturated with a non-conductive, water insoluble flameproof compound incapable of being decomposed to a conducting medium, fillers of asbestos in the spaces between said conductors, an asbestos layer saturated with a non-conductive,
5. An electric cable comprising in combination a plurality of electric conductors, each surrounded with layers of asbestos rovings and an intermediate glass wool layer, said layers being saturated with a non-conductive, water insoluble flameproof compound incapable of being decomposed to a conducting medium, fillers of asbestos saturated with flameproof compound similar to the first mentioned compound in the spaces between said conductors, an asbestos layer saturated with flameproof compound similar to the first mentioned compound enclosing said assembly, a tape filled with a polymerized vinyl halide surrounding the last mentioned asbestos layer, and a polymerized vinyl halide layer about said tape.

water insoluble flameproof compound enclosing said assembly, and a polymerized vinyl halide layer surrounding the last mentioned asbestos layer.

5. An electric cable comprising in combination a plurality of electric conductors, each surrounded with layers of asbestos rovings and an intermediate glass wool layer, said layers being saturated with a non-conductive, water insoluble flameproof compound incapable of being decomposed to a conducting medium, fillers of asbestos saturated with flameproof compound similar to the first mentioned compound in the spaces between said conductors, an asbestos layer saturated with flameproof compound similar to the first mentioned compound enclosing said assembly, a tape filled with a polymerized vinyl halide surrounding the last mentioned asbestos layer, and a polymerized vinyl halide layer about said tape.

WILLIAM F. LAMELA.
